UNITED STATES PATENT OFFICE

2,279,638

AUTOMATIC NAILING MACHINE

Gerald C. Paxton and Glenn M. Criger, Riverside, Calif., and Walter Hale Paxton, deceased, late of Riverside, Calif., by Geraldine Paxton and H. S. Nicks, executors, Riverside, Calif., assignors to Food Machinery Corporation, San Jose, Calif., a corporation of Delaware

Application November 13, 1939, Serial No. 304,162

59 Claims. (Cl. 1—14)

This invention relates to box nailing machines and is particularly useful in making small boxes at a high rate of production.

Extremely large quantities of small wooden boxes are used annually in the marketing of cigars, cheese and other products. A single firm in the United States, for example, uses 72,000,000 small boxes annually. Heretofore, these boxes have been made on hand fed or semi-automatic machines and large numbers of such machines and operators have been required to produce these boxes.

An object of the present invention is to provide a machine for making small boxes at a high rate of production while requiring the services of a minimum number of operators.

The shook used in the manufacture of small boxes is so thin that it often warps, thus making it difficult to handle and nail. Previous attempts to provide full automatic machines for assembling and nailing such shook have failed to solve the problem of handling warped shook automatically without jamming the machine or producing imperfect boxes.

A further object of this invention is the provision of such a machine having means for preventing interference with the operation thereof by warped shook.

As the above mentioned boxes are made in many different sizes and proportions, it is highly desirable that such a machine be readily adjustable to handle different sized shook and produce boxes of various sizes.

Accordingly, a still further object of our invention is to provide a box making machine which is readily adjustable to make boxes of a wide range of sizes.

Other objects and advantages will become apparent in the following description taken in connection with the accompanying drawings, in which:

Fig. 1 is a front elevational view of a preferred embodiment of the box making machine of our invention.

Fig. 1A is a perspective view of a box of the general type and proportion for which the machine shown in Fig. 1 is adjusted to make.

Fig. 2 is a vertical sectional view of the machine taken on the line 2—2 of Fig. 1.

Fig. 2A is a fragmentary perspective view of a portion of the frame of the machine of our invention, showing a gib on which one of the nailing heads is guided.

Fig. 3 is a horizontal sectional view taken on the line 3—3 of Fig. 1.

Fig. 4 is an electrical wiring diagram showing the manner in which the electrical elements of the machine are wired.

Fig. 5 is a vertical sectional view taken on the line 5—5 of Fig. 2 and showing the lower portion of the machine.

Fig. 6 is a fragmentary vertical sectional view taken on the line 6—6 of Fig. 5.

Fig. 7 is a horizontal sectional view taken on the line 7—7 of Fig. 1.

Fig. 7A is a detail perspective view of one of a pair of adjustable frame members included in the machine of our invention.

Fig. 8 is an enlarged, fragmentary plan view of the central portion of the machine as seen in Fig. 7, Fig. 8 showing end and side shook in the magazines provided therefor with the innermost pieces of this shook disposed against the shook assembling form in position to be elevated thereby.

Fig. 8A is a fragmentary view of one corner of the box form shown in Fig. 8, showing the relationship of the side shook to a piece of end shook of less than average length.

Fig. 8B is a view similar to Fig. 8A but showing how the side shook flexes into contact with a short piece of end shook when engaged by a nail chuck.

Fig. 9 is a fragmentary view similar in part to Fig. 8 and showing the manner in which the side and end shook is retained in the magazines by the shook assembling form after completion of a box and prior to the next successive shook picking operation.

Fig. 10 is a fragmentary, elevational view looking in the direction of the arrow 10 of Fig. 8 and shows the manner in which one of the vertically adjustable corner plates of the side and end shook magazines is mounted.

Fig. 11 is an enlarged perspective view of the reciprocating shook assembling form included in the machine of our invention.

Fig. 12 is a fragmentary, vertical sectional view taken on the line 12—12 of Fig. 11.

Figs. 13 to 16 inclusive are fragmentary sectional views taken on the line 13—13 of Fig. 11 and showing the manner in which the shook assembling form is supplied with shook, the successive positions shown in these figures being as follows:

Fig. 13 shows the shook assembling form descending after a box making operation.

Fig. 14 shows the shook form still descending with an adjacent piece of side shook tilting into position against the form.

Fig. 15 illustrates the form at its lowermost position with the nearest piece of side shook ejected from the magazine into position against the form.

Fig. 16 shows the form rising with the aforesaid piece of side shook retained thereon by suitable springs engaging the upper edge of the shook and lugs engaging the lower edge thereof.

Fig. 17 is an enlarged, fragmentary sectional view taken on the line 17-17 of Fig. 1 and showing the shook magazines empty.

Fig. 17A is an enlarged, fragmentary view showing means for adjusting the length of certain rods of the machine shown in Fig. 17.

Fig. 18 is a fragmentary view similar to Fig. 17 but taken at a higher level on the machine as indicated by the line 18-18 of Fig. 1.

Fig. 19 is an enlarged, vertical sectional view taken on the line 19-19 of Fig. 2 showing end shook in the magazines provided therefor and showing the shook assembling form in its lowermost position.

Fig. 19A is a perspective view of one of a pair of horizontal frame members of the machine on which the pieces of bottom shook slide while being fed from the magazine into position over the shook assembling form, these frame members also serving to carry finished boxes as the latter are being discharged from the machine.

Fig. 20 is an enlarged perspective view of one of the horizontal chuck carriers included in the nailing mechanism of the machine.

Fig. 21 is a perspective view of the nail chuck shown in Fig. 20 illustrating the manner in which the chuck is taken apart.

Fig. 22 is an enlarged, horizontal sectional view taken on the line 22-22 of Fig. 20.

Fig. 23 is a vertical sectional view taken on the line 23-23 of Fig. 22 showing the internal construction of the nail chuck disclosed in Figs. 20, 21 and 22.

Fig. 23A is a perspective view of one of a pair of vertically reciprocal heads on which the nail chucks of the machine are mounted, most of the parts being removed from the head to more clearly show the formation of the latter.

Fig. 24 is an enlarged, fragmentary, vertical sectional view taken on the line 24-24 of Fig. 7 showing the mechanism for operating a switch to stop the machine when the shook magazine thereabove is almost empty.

Fig. 25 is an enlarged, fragmentary, perspective view looking in the direction of the arrow 25 of Fig. 28 showing the switches for stopping the machine in the event of failure of the bottom shook feeding mechanism or box ejecting mechanism.

Fig. 26 is an enlarged, fragmentary, vertical sectional view taken on the line 26-26 of Fig. 17 showing one of the box strippers for removing finished boxes from the shook assembling form.

Fig. 27 is a fragmentary, vertical sectional view taken on the line 27-27 of Fig. 26 and shows one of the feed dogs for feeding pieces of bottom shook into position over the shook assembling form of the machine.

Figs. 28, 29, 30 and 31 are enlarged, fragmentary, vertical sectional views taken on the same plane as Fig. 2, these views illustrating successive stages in the operation of the machine during fabrication of a box.

Fig. 28 shows the shook assembling form during its upward movement at the moment of stripping pieces of side and end shook from the

magazines, this view also showing the ejection of previously made boxes and the feeding of a piece of bottom shook into the path of the rising shook assembling form.

Fig. 28A is a fragmentary operation view of certain portions of the machine shown in Fig. 2, the scale of Fig. 28A being the same as that of Fig. 2 and half that of Fig. 28. The positions of the elements shown in Fig. 28A correspond with the positions in Fig. 28 of the shook assembling form and bottom shook feeding and box ejecting dogs.

Fig. 28B is a fragmentary, vertical sectional view in reduced scale showing the manner in which the side and end shook magazines of the machine are supplied with shook without stopping or otherwise interrupting operation of the machine.

Fig. 29 shows the shook assembling form with a set of shook assembled thereon just as the shook on the rising form contacts the vertically reciprocal nailing head. This view also shows the shook feeding and box ejecting dogs being moved rightward in preparation for the next shook feeding and box ejecting operation.

Fig. 29A is a view similar to Fig. 28A but showing a successive position of the elements which cause the shook assembling form and shook feeding and box ejecting dogs to be positioned as shown in Fig. 29.

Fig. 30 shows the shook assembling form elevated to its uppermost position after it has lifted the nailing heads causing the latter to drive nails in each end of the sides and bottom of a box to complete the formation of the latter.

Fig. 30A is a view similar to Figs. 28A and 29A and shows the elements thereof in corresponding positions relative to the positions of the form and dogs as shown in Fig. 30.

Fig. 31 shows the shook assembling form nearing its lowermost position just after the stripping of a finished box therefrom, this view also showing the shook feeding and box ejecting dogs disposed in rightwardmost position with the ejector dog in position to remove the said finished box leftward out of the path of the vertically reciprocating form.

Fig. 31A shows the positions of the power transmitting elements which cause the form and dogs to be positioned as shown in Fig. 31.

Fig. 32 is a fragmentary vertical sectional view taken on the line 32-32 of Fig. 31 and showing a finished box resting on the strippers just after being stripped from the shook assembly form.

Fig. 33 is an enlarged, fragmentary vertical sectional view taken on the line 33-33 of Fig. 31 but showing the finished box still on the form at the moment of engagement of the box by the strippers.

Fig. 34 is a perspective view of one side of the upper portion of the machine looking in the direction of the arrow 34 of Fig. 7.

Referring specifically to the drawings, a box making machine 10, comprising a preferred embodiment of our invention, is shown generally in Figs. 1 and 2, the machine 10 including a base 11, a pair of adjustable frame structures 12 and 13 (see Figs. 1 and 34), a power mechanism 14 (see Figs. 2 and 3), shook assembling form 15 (see Figs. 2, 11 and 12), side and end shook feeding mechanism 16 (see Figs. 1, 2, 7, 8, 9, 10), bottom shook feeding and box ejecting mechanism 17 (see Figs. 2, 17, 19, 19A, 28, 29, 30, 31 and 34), and nailing mechanism 18 (see Figs. 1, 2, 18, 19 and 28).

Before continuing with the specific description of the structure of our invention, we will point out its general mode of operation. The shoo⁵ assembling form 15 is reciprocated vertically over a given operating path, each cycle of operation beginning with this form in its lowermost position. As it starts to rise, this form picks up two pieces of end shoo¹⁰ and two pieces of side shoo¹⁵ to form the ends and sides of a box. Continuing upward, this form receives a piece of bottom shoo²⁰ disposed horizontally and then rises into contact with the nailing mechanism before it has completed its upward movement. The final upward movement of the shoo²⁵ assembling form 15 lifts portions of the nailing mechanism, thereby operating the latter to drive nails both horizontally and vertically such as are necessary to completely unite the box parts assembled on the form. As the form then returns downwardly, the finished box is stripped therefrom by stationary strippers and ejected from the operating pathway of the form by the same movement which feeds in a new bottom part for the next box forming operation.

The base 11

The base 11 as shown in Figs. 1, 2, 3, 5, 6 and 7, includes a base plate 20, upon which a housing 21 is mounted, the latter including side walls 22 as shown in Figs. 3 and 5, and front and rear walls 23 and 24 respectively, as shown in Figs. 2, 3 and 7. Bolted to the rear wall 24 and the base plate 20 as seen in Figs. 2 and 3 is a motor housing 25. As shown in Figs. 2 and 7, the upper edges of the front and rear walls 23 and 24 are formed to provide T slots 28. Mounted in a socket plate 30 provided on the base plate 20 is a pair of vertical tubes 31 as shown in Figs. 2 and 3, these tubes being joined at the upper extremities thereof by a cross bar 32 (see Figs. 2 and 19). Extending from the bar 32 to the front wall 23 of the housing 21 is a V brace 33 as shown in Figs. 2, 11 and 18.

The frame structures 12 and 13

The frame structures 12 and 13 include a pair of cast cross members 34 adjustably mounted on top of the housing 21 as shown in Figs. 7, 7A, 17, 18 and 19. Each of the cross members 34 (see Figs. 7 and 7A), includes bosses 35 having set screws 36 provided thereon, and extending inwardly from the bosses 35 are projections 37. Between the bosses 35 of each of the members 34 is a plate 38 having slots 39 formed there-through. The members 34 are secured to the front and rear walls 23 and 24 of the housing 21 by bolts 40 extending into the aforementioned T slots 28, the bolts 40 having nuts 40A thereon. Adjustable vertically in the bosses 35 of the cross members 34 are four posts 41, the latter being secured vertically by the set screws 36. Mounted on the posts 41 of each of the frame structures 12 and 13 as seen in Figs. 1, 24, 19 and 34, is a cross bar 42 bored at its ends to receive the posts 41 and having set screws 43 for locking the cross bar 42 on the posts 41. Fixed on top of the bar 42 are rubber bumpers 44 for a purpose described hereinafter. Mounted centrally on each of the cross bars 42 as seen in Figs. 2A and 19 is a vertical column 45 shaped in cross section as seen in Fig. 18. Formed centrally through the column 45 is an opening 46 referred to hereinafter. As seen in Figs. 1, 2 and 19, the upper end of each of the columns 45 is secured to a head casting 47 mounted on the upper ends of the posts 41 of 70 75

each of the frame structures 12 and 13, the castings 47 being referred to later relative to the nailing mechanism 18.

The power mechanism 14

The power mechanism 14, shown in Figs. 2, 3, 5 and 6, includes a crank shaft 48, rotatably supported on the base plate 20 by a casting 49 formed to provide bearings 50 and 51. Fixed on the shaft 48 as seen in Fig. 5 is a crank 52 having a crank pin 53 and mounted on the shaft 48 between the bearings 50 and 51 is a fly wheel 54, and a small sprocket 55. On the end of the shaft 48 adjacent the bearing 51 is a large double sprocket 56 and a cam 57. As shown in Fig. 6, the cam 57 is formed to provide a lobe 58, an arcuate depression 59, and curved portions 60 and 61. As shown in Figs. 5 and 6, a lever 64 is pivotally mounted in a clevis 65 provided on the base plate 20, the lever 64 having three pins 66, 67 and 68 extending transversely therethrough and a finger 69 at the free end thereof, a set screw 70 being threadedly mounted in the finger 69. Mounted on the base 20 below the finger 69 25 of the lever 64 is a switch 72, the purpose of which will be described hereinafter. Mounted on the pin 67 of the lever 64 is a roller 74 and a connecting rod 75. As shown in Figs. 3 and 6, the roller 74 is positioned for engagement with the periphery of the cam 57.

Journalled in bearings 78 and 79 formed on the back wall 24 of the housing 21 as seen in Figs. 5 and 6 is a horizontal oscillating shaft 80 having an arm 81 fixed on one end thereof, the latter being joined to the upper extremity of the connecting rod 75 extending from the lever 64. Fixed on the shaft 80 between the bearings 78 and 79, as shown in Figs. 5, 6 and 19, is a pair of bifurcated arms 82 having idle sprockets 83 mounted in the ends thereof.

Mounted on the base plate 20 within the housing 25 as shown in Figs. 2, 3, 5 and 6, is a motor M, the latter being of conventional design and including a built-in speed reducing unit 86 and an electrically operated brake mechanism 87, the latter being adjustable by means of a lever 88 as shown in Figs. 2 and 3. Extending from the speed reducing unit 86 of the motor M is a drive shaft 89 having a cone 90 keyed thereon as shown in Fig. 3. Frictionally mounted on the cone 90 is a small double sprocket 91 retained in frictional engagement with the cone 90 by a cap screw 92 and washer 93. Trained about the double sprockets 91 and 56 is a chain 94 for transmitting rotation of the motor M to the crank shaft 48. Mounted on the base plate 20, as shown in Figs. 2 and 3, is a pair of bearings 96 in which a shaft 97 is rotatably mounted, the latter having cranks 98 fixed on opposite ends thereof, the purpose of the latter being described hereinafter in relation to the nailing mechanism 15. Fixed on the shaft 97 is a sprocket 99, the latter being driven from the crank shaft 48 by a chain 100 trained about the sprocket 55.

Mounted on the rear wall 24 of the housing 21 as seen in Figs. 2, 5 and 6, is a bracket 105 having a pin 106 on which a lever 107 is pivoted. The lever 107 is bifurcated at its extremity as shown in Fig. 5 and has a pin 108 extending there-through on which a link 109 is pivoted. Extending transversely through the bifurcated end of the lever 107 are three holes 110, 111 and 112 in which a pin 113 may be selectively mounted. Extending from the pin 113 to the crank pin 53 of the crank 52 is a connecting rod 114 adjustable

by means of a turnbuckle 115 as shown in Figs. 2 and 5.

The shook assembly form 15

The form 15 shown in Figs. 2, 7, 8, 9, 11 to 18 incl. and 28 is formed of cast metal, as shown in Fig. 11, to provide a head portion 118 and a skirt portion 119 formed integral with and extending downward from the head portion 118. Extending around the form 15 is a groove 120. The head portion 118 is smaller in length and width than the skirt portion 119 to provide side shoulders 121 and end shoulders 122, the head 118 having side faces 123 and end faces 124, the portions of the head 118 adjacent the side faces 123 being relieved as indicated at 123' in Fig. 11. Mounted in channels 125 formed on the upper surface of the head portion 118 are leaf springs 126. Formed in the end faces 124 of the head 118 are openings 127 (see Fig. 12) in which yieldable plungers 128 are mounted, these being urged outward by springs 129. As shown in Fig. 11, two corners of the head portion 118 are cut away to form notches 130, the latter providing clearance for box ejecting dogs described hereinafter.

The width of the head portion 118 of the form 15 (the distance between the side faces 123), is slightly greater than the inside width of the box which the machine 10 is adjusted to make while the distance between the end faces 124 is slightly less than the inside length of the box, the purpose of this being described hereinafter.

Fixed on opposite sides of the form 15 by screws 131 is a pair of lugs 132, upper edges 133 thereof being sharpened and projecting above the shoulders 121 as seen in Figs. 11 and 13. Mounted on the underside of the head portion 118 as seen in Fig. 12 is a pair of rods 134 reduced in diameter at upper portions thereof to provide shoulders 135. Extending through holes 136 in the head portion 118 are cap screws 137 threaded into upper ends of the rods 134. Secured on the underside of the head 118 is a clevis bracket 140, the latter being engaged by the shoulders 135 of the rods 134 and clamped in position by the cap screws 137. Extending through the clevis 140 is a pin 141 on which the upper end of the connecting rod 109 is pivoted. The rods 134 are slidably received by the tubes 31 so as to guide the form 15 during vertical reciprocation thereof.

The side and end shook feeding mechanism 16

The shook feeding mechanism 16, as shown in Figs. 7 and 8, includes magazines 150 extending laterally from opposite sides of the machine 10 for receiving and feeding box ends E. Extending from the front and rear sides of the machine 10 as shown in Fig. 7 are similar magazines 151 for receiving and supporting box side shook S. Each of the magazines 150 includes a pair of angle irons 153, the latter being adjustably mounted on the plates 38 of the cross members 34 by screws 154 extending through the slots 39. The angle irons 153 are held in spaced relation at their outermost extremities by tie rods 155 as shown in Fig. 7, the rods 155 extending through blocks 156 provided on the underside of the outer ends of each of the angle irons 153, the rods 155 being secured to the blocks 156 by set screws 157 (see Fig. 24). Extending from the tie rods 155 to the side walls 22 of the housing 21 are rods 158 as shown in Figs. 7 and 24. Slidable on each pair of the rods 158 is a casting 159 having a rod 160 slidably vertically therethrough, the latter having a head 161 and a handle 162. Threaded into the casting 159 (see Fig. 24) is a stud 163 on which

a pair of collars 164 and 165 is threaded. The peripheries of the collars 164 and 165 are formed to threadedly engage the ends of a pair of springs 166 and 167. Extending through a hole 168 provided in the side wall 22 of the housing 21 is a tube 169 having collars 170 and 171 thereon, the collar 171 being welded on the tube 169 as shown in Fig. 24. The collars 170 and 171 are fixed to inner ends of the springs 166 and 167. Mounted on the innermost extremity of each of the tubes 169 is a U-shaped clip 172 (see Figs. 7 and 24), the latter being clamped against the wall 22 by a block 173 threaded on the end of the tube 169. Mounted in the clip 172 is a switch 174. Loosely mounted within the tube 169 is a rod 175, the latter opening the normally closed switch 174 when engaged by the collar 165 as seen in Fig. 24.

The magazines 151 are identical in construction with the aforescribed magazines 150, except that the magazines 151, as shown in Fig. 7, are secured to the projections 37 of the cross members 34 by bolts 177 extending through T-slots 178 provided in the angle irons 153. Similar reference numerals are used to denote similar parts in each of the magazines 150 and 151.

As shown in Figs. 8, 9 and 10, adjacent ends of each pair of the angle irons 153 of the magazines 150 and 151 are welded together and have tubes 180 welded thereto in the internal angles formed by these angle irons as seen in Fig. 10. Slidable vertically in each of the four tubes 180 is a square post 181 adjustably secured to the tube 180 by means of a set screw 182. Welded on top of the post 181 is a head 183 to which a corner plate 184 is adjustably mounted by means of cap screws 185. Each of the plates 184 includes a portion 186 extending over the adjacent magazine 150 and a portion 187 extending over the adjacent magazine 151. Extending upwardly from each of the plates 184 is an angle iron guide 188.

The bottom shook feeding and box ejecting mechanism 17

The mechanism 17 shown in Figs. 2, 17, 19, 19A, 28 and 34 is mounted on the posts 41 of the frame structures 12 and 13 by means of pairs of front and rear collars 195 and 196 respectively secured on the posts 41 by set screws 197 as shown in Figs. 17 and 19. Formed integral with each of the collars 195 and 196 is a projection 198 and formed on the rear collars 196 are ears 199 (see Figs. 17 and 34), having idle sprockets 200 rotatably mounted on extremities thereof. Mounted on the projections 198 of the collars 195 and 196 is a pair of right and left hand shook slides 205 and 206 respectively, the right hand slide 205 being shown in Fig. 19A, similar reference numerals being used to describe each of the slides 205 and 206. The slide 205 includes front and rear angle iron portions 207 and 208 respectively welded at their innermost ends to a bar 209. Welded centrally on the bar 209 is a plate 210 having a hole 211 at its upper extremity, a threaded hole 212 at its lower extremity and a pair of holes 213 formed centrally therethrough. Welded on top of the angle irons 207 and 208 are pairs of apertured ears 215 and 216, these being aligned with the hole 211 of the plate 210. Mounted on the angle irons 207 and 208 are blocks 218 and 219 having holes 220 and 221 extending therethrough, these being aligned with the holes 213 of the plate 210.

Mounted on the angle iron portions 208 of the slides 205 and 206, as shown in Figs. 2, 17 and 28, is a bottom shook magazine 224 including vertical angle irons 225 having adjustable shook gates 227 mounted on the lower extremities thereof, one of these being shown in Fig. 28. Mounted on each of the angle irons 225 of the magazine 224 is a side plate 230 formed to provide horizontal slots 231 (see Figs. 2 and 34). Adjustably mounted on each of the plates 230 is an angle iron 234, the latter being secured thereto by bolts 235 extending through the slots 231. Supported within the magazine 224 between the angle irons 225 and 234 is a stack of bottom shook B as seen in Fig. 28.

As shown in Fig. 25, pairs of upper and lower bearings, 238 and 239 respectively, are provided on portions of the plates 230 which extend forward from the angle irons 225. Rotatable in the bearings 238 is a shaft 242 having a collar 243. This shaft also has a collar 243a disposed just inside one of the bearings 238, this collar having a finger 244 secured thereon. Fixed on the plate 230 of the shook slide 206 is a normally open switch 246 positioned to be operated by the finger 244. Fixed centrally on the shaft 242 as shown in Figs. 18, 25 and 28, is a lever 248 having a slotted end 249 and an ear 250. Mounted on the under side of the lever 248 as shown in Fig. 28 is an arm 251, the latter extending over the shook assembling form 15. As seen in Fig. 18, a pair of arms 254 is freely mounted on the shaft 242 adjacent opposite sides of the lever 248, these arms being adjustably secured to the lever 248 by a bolt 255, the latter extending through the slotted end 249 of the lever 248. Secured to the arms 254 is a U-shaped extension 256.

Pivotaly connected to the ear 250 of the lever 248 and extending upwardly through a rod 258 extending transversely through upper extremities of the side plates 230, as shown in Figs. 2 and 19, is a vertically yieldable link 259 having a compression spring 260 thereon and a head 261 formed on the upper extremity thereof. The rod 258 is provided for limiting downward movement of the lever 248, the spring 260 being provided to yieldably urge the lever 248 and parts attached thereto downward into the position in which they are shown in Figs. 2 and 28.

Rotatable in the bearings 239 below the shaft 242 is a similar shaft 264 having a finger 265 fixed thereon, the latter being positioned to operate a normally closed switch 266 mounted on the plate 230 of the shook slide 205 as shown in Fig. 25. Fixed centrally on the shaft 264 is an arm 267 formed as shown in Fig. 28.

Extending through the pairs of ears 215 and 216 of each of the shook slides 205 and 206 as seen in Figs. 17 and 19 is a rod 270. Swingable on each of the rods 170 between the pairs of ears 216 of each of the slides 205 and 206 is an arm 271 having a pointed rod 272 welded on the extremity thereof, the latter having a plurality of threaded extension sections 273 provided on one end thereof as seen in Figs. 17 and 17A. Coiled about the rods 270 are torsion springs 274 provided for the purpose of urging the arms 271 downward in a manner to be described herein-after.

Pivotaly mounted on the rod 270 between the pairs of ears 215 of each of the shook slides 205 and 206 is an arm 276 having a pointed bar 277 welded on the end thereof, the bar 277 having threaded extension sections 278 provided for adjusting the length thereof. Torsion springs 75

279 are mounted on the rod 270 between the ears 215 for urging the arm 276 downward. Pivoted centrally on the rod 270 of each of the shook slides 205 and 206 is a pair of box strippers 281 as seen in Figs. 17, 26 and 27. Each of the strippers 281 is formed to provide a ledge 282 beveled on the under side thereof as indicated at 283. Extending outwardly from each of the strippers 281 is a lug 284 having a stop screw 285 threaded therethrough, the latter engaging the bar 209. Mounted between the bar 209 and each of the strippers 281 is a pair of compression springs 286 provided for urging the strippers into the position shown in Fig. 26.

15 As shown in Figs. 17, 19 and 19A, a pair of rods 289 is slidably mounted on each of the shook slides 205 and 206. The rods 289 slide in the aforementioned holes 213, 220 and 221 of the slides 205 and 206. Forward ends of the rods 289 are joined by plates 290 (see Fig. 17) and extending from the plate 290 of each pair of rods 289 to the central plate 210 (see Figs. 17 and 28), is an extension spring 291, the latter urging the pair of rods 289 associated therewith rearwardly of the machine. The pairs of rods 289 are reciprocated during operation of the machine 10 by the shaft 80 shown in Figs. 5 and 28, the motion of the shaft 80 being transmitted to the rods 289 by chains 292, the latter extending from blocks 293 fixed on the rods 289, about the sprockets 280 and 83, to anchor blocks 294 provided on the underside of the projections 37 of the cross members 34 as shown in Fig. 28.

Adjustably mounted on each pair of the rods 289 as shown in Figs. 17 and 28 are bottom shook feed dogs 295, 296 and 297, each of these, as shown in Figs. 26 and 27, being pivoted on a bracket 293 by means of a screw 299 and urged upward by springs 300.

40 As shown in Figs. 17, 18 and 28, a bracket 303 is mounted on each pair of the rods 289. Pivoted on each of the brackets 303 by means of a screw 304 is a box ejector dog 305 having a spring similar to the springs 300 of the dogs 295, 296 and 297, for urging the dog 305 upward to the position in which it is shown in Fig. 28. Mounted on the angle iron portions 207 of each of the shook slides 205 and 206 is an inclined, angle iron track 307 for the purpose of elevating finished boxes as shown in Fig. 28 and delivering the boxes to a point of discharge from the machine 10.

The nailing mechanism 18

The nailing mechanism 18, shown in Figs. 1, 2, 18, 19, 20 to 23A inclusive and 28, includes a pair of identical heads 312, one of which is shown in Fig. 23A with the parts removed therefrom so as to more clearly show the construction thereof. The head 312 is preferably cast to provide a horizontal, channel-shaped portion 313 having bosses 314 formed integrally therewith. The bosses 314 are bored to slidably receive the posts 41 of the frame structures 12 and 13 as shown in Figs. 18 and 23A. Formed in the channel portion 313 is a pair of slots 315. Formed integrally with the head 312 is an upstanding portion 316 having a vertical slideway 317 extending therethrough, and facing outwardly therefrom, the latter slidably receiving the column 45 of the frame structure 12 as shown in Figs. 18, 19 and 34. Formed on the upstanding portion 316 is a plurality of horizontal keyways 318 and tapped holes 319 as seen in Fig. 23A. Mounted on opposite ends of the channel portion 313 of each of the heads 312 are plates 320 and 321 having bores 322. The

plates 321 have apertured ears 323 extending from the uppermost sides thereof as shown in Figs. 1, 2, 23A and 28. Provided on each of the four posts 41 between the heads 312 and the upper castings 47 is a compression spring 324.

Fixed centrally on each of the channel portions 313 of the heads 312 (see Figs. 18 and 19), is a block 326 having a bore 327. Mounted on the block 326, as shown in Figs. 18, 19 and 28 is a yieldable flushing plate 328 urged away from the block 326 by a compression spring 329.

Rotatable within the channel portion 313 of each of the heads 312 is a nail driving screw 332 having a pinion 333 formed centrally thereon, the latter being journalled in the bore 327 of the block 326. Extending from opposite sides of the pinion 333 are right and left hand threaded portions 334 and 335 respectively, the threads thereof having a relatively long lead as shown in Fig. 18.

Formed on opposite ends of each of the screws 332 are studs 336 journalled in the bores 322 of the plates 320 and 321. The screws 332 are rotated in response to vertical movement of the heads 312 by racks 337 adjustable vertically in the openings 46 of the columns 45 by means of plates 338 as seen in Figs. 18 and 19, the toothed faces of the racks 337 meshing with the pinions 333 of the screws 332.

Slidably mounted on the channel portion 313 of each of the heads 312, as seen in Fig. 18, is a pair of nail chuck carriers 340 and 341, these being identical except that the carriers 340 are adapted to fit on the right hand threaded portions 334 of the screws 332 while the carriers 341 fit on the left hand portion 335, similar reference numerals being used to denote similar parts of each of the carriers 340 and 341.

One of the carriers 340 is shown in detail in Figs. 20, 22 and 23 and includes a body 342 bored as indicated at 343 to slidably receive the screw 332, the bore 343 being counter-bored at one end thereof as indicated at 344 in Fig. 22. Formed integrally with the body 342 is a vertically disposed gib 345 upon which one or a plurality of horizontal nail chucks 346 may be mounted. Rotatable in the counterbore 344 is a nut 348 threaded on the screw 332 and retained by a plate 349 mounted by suitable screws on the body 342. Provided between the nut 348 and plate 349 is a ring 350 having a plurality of pins 351 fixed thereon and extending into holes 352 drilled in the nut 348. Within each of the holes 352 is a compression spring 353 for urging the nut 348 and ring 350 into frictional engagement with the body 342 and plate 349. Formed in the body 342 is a vertical channel 354, movement of the carrier 340 relative to the head 312 being limited by a block 355 secured to the channel portion 313 of the head 312 by a cap screw 356 extending through the slot 315, the block having faces bearing against interior faces of the channel 313.

Each of the chucks 346, as shown in Figs. 20 to 23, includes a body 358 formed to fit on the gib 345 of the carrier 340 and secured thereto by a set screw 359. Formed in the body 358 is a longitudinal channel 360 and a pair of angular channels 361. Pressed into the body 358 is a pair of pins 362 having notches 363 formed on opposite sides thereof. Pivotable on the pins 362 are nail guiding jaws 364, these being urged inward by springs 365 as shown in Fig. 23. Removably mounted on each of the chucks 346 is a cover plate 368. Formed on the plate 368 is a notch 369 and a nail receiving opening 370. The

cover plate 368 is yieldably retained in position against the chuck body 358 by a spring clip 371, the latter being received by the notches 363 of the pins 362. Formed at one end of the clip 371 is a bight 372 received by the notch 369 so as to retain the clip 371 against accidental displacement from the cover plate 368. The chuck 346 may be readily disassembled as shown in Fig. 21 by manually lifting the clip 371 free from the notch 369 and sliding the clip rightward from engagement with the pins 362 to permit removal of the cover plate 368 from the chuck body 358.

As shown in Figs. 18 and 28, a nail driving head 375 is threaded on the screws 332 adjacent each of the chuck carriers 340 and 341. Each of the heads 375 includes a block 376 slidable on the channel portions 313 of the heads 312 and threaded on the screw 332. Yieldably mounted in each of the blocks 376 by means of springs 377 is a block 378 retained in position by a plate 379. Keyed to the block 378 is a nail driving punch 380, the latter extending into the channel 360 of the chucks 346.

Mounted on the upstanding portion 316 of each of the heads 312 as seen in Figs. 19 and 28, is a horizontal gib 383, the latter having a key 384 received by a selected one of the keyways 318. Fixed on each of the gibs 383 is a pair of vertical nail chucks 385, these being identical with the horizontal chucks 346 and bearing similar reference numerals. Mounted on each of the gibs 383 adjacent the vertical chucks 385 (see Fig. 28) is a plurality of feet 386, the rearmost pair of the latter having flusher fingers 387 extending downward therefrom.

As shown in Figs. 19 and 28, a nail driving head 388 is mounted on each of the columns 45 above the heads 312. Ears 389 (see Fig. 34), formed on the head 388, embrace the edge portions of the column 45 to retain the head in vertically slidable relation to the column 45. Formed through the upper end of each of the heads 388 is a slot 390, a cap screw 391 extending through the slot 390 into the column 45, the screw 391 being provided for limiting vertical movement of the head 388 as well as retaining the latter against the column 45. Mounted on the heads 388 by means of clips 392 are nail driving punches 393, lower ends of the latter extending into the vertical chucks 385. Formed on each of the nail driving heads 388 (see Fig. 28), is a pair of bosses 395 bored to receive lower ends of a pair of compression springs 396. Fixed on each of the columns 45 above the nail driving heads 388 is an angle bracket 397 having a pair of cap screws 398 threaded therethrough, lower extremities of these extending into the springs 396. Threaded on the screws 398 are nuts 399 for adjusting the pressure exerted by the springs 396 on the nail driving head 388.

Included in the nailing mechanism 18, as seen in Figs. 1, 2, 19 and 34, are identical nail feeding units 402 and 403 mounted on the aforementioned castings 47 at the upper extremities of the posts 41. Each of the units 402 and 403 includes a nail stripper pan 404 pivoted on bolts 405 provided on the casting 47. Extending from each of the pans 404 to the cranks 98 on the shaft 97 shown in Fig. 3 is a connecting rod 406 for oscillating the pan 404 in a manner familiar in the nailing machine art. Slidable horizontally on each of the castings 47, as shown in Figs. 2 and 19, is a conventional nail pick bar 407, the latter (see Fig. 2) having a stop 408 and roller 409 on

opposite ends thereof. Extending from the bar 407 to the casting 47 is a spring 410 for urging the bar 407 rightward as seen in Fig. 2.

Pivoted on each of the castings 47 is a cam 413 connected by a link 414 to the ear 323 of the plate 321 as shown in Fig. 1. Vertical movement of the heads 312, as described later, is transmitted by the links 414 to the cams 413, the latter causing the pick bars 407 to reciprocate horizontally.

Mounted on each of the castings 47, as best shown in Figs. 2, 19 and 34, is a series of bars 417 spaced to provide nail runs 418, the latter delivering nails from the pans 404 to the pick bars 407. Mounted below the lower ends of each of the nail runs 418 is a nail funnel 419. Extending from certain of the funnels 419 to the vertical and horizontal nail chucks 385 and 346 respectively (see Fig. 2) are nail tubes 420, the latter being telescopic to permit vertical movement of the chucks relative to the stationary funnels 419.

As seen in Fig. 2, ten of the nail runs 418 and funnels 419 are provided on the nail feeding unit 402, the same number being included in the opposite nail feeding unit 403. When less than ten nails are required for each end of a box to be made on the machine 10, the nail stripping slots 421 (see Fig. 34) of the nail pans 404 which are not required are closed. In the present disclosure, the machine 10 is shown as being adjusted to make a box requiring but four nails at each end thereof, six of the ten slots in each of the pans 404 being closed in a manner well known in the art.

Referring now to the wiring diagram shown in Fig. 4, the electrical apparatus of the machine 10 includes the aforementioned motor M, the four switches 174 of the side and end shook feeding mechanism 16, the switch 72 on the base plate 20 (see Fig. 6) and the switches 246 and 266 shown in Fig. 25. In addition to the motor and switches above referred to, the electrical apparatus also includes a pair of 3-pole magnetic switches 423 and 424 and a quadruple push button switch 425. The magnetic switches 423 and 424 are mounted in a housing 426 provided on the base plate 20 as seen in Figs. 2 and 3 and the quadruple switch 425 is mounted on the front wall 23 of the housing 21 as shown in Figs. 1 and 2.

As shown in Fig. 4, the magnetic switch 423 includes three terminals *a* to which three lead wires 430 of a three-phase electrical circuit are connected. Provided in the magnetic switch 423 for engagement with the contacts *a* are three blades *b*, these being connected to the motor M by wires 431, 432 and 433. Included in the switch 423 is a coil 434 for actuating a core 435, the latter engaging contacts *c* and *d* when the coil 434 is energized.

The magnetic switch 424 serves to reverse the motor M as mentioned hereinafter, the switch 424 including three contacts *e* connected by wires 438, 439 and 440 to the lead wires 430. Blades *f* are included in the switch 424, these being connected by wires 443, 444 and 445 with the wires 431, 432 and 433 respectively. The blades *f* of the switch 424 are actuated by a coil 446, one end of the latter being connected to one end of the coil 434 of the switch 423 by a wire 447 joined with the wire 439.

The electric brake 87 of the motor M includes a pair of coils 449 and 450, adjacent ends of

which are joined to a single wire 451 leading to the wire 432. The remaining end of the coil 449 is connected by a wire 452 with wire 433 while the remaining end of the coil 450 is joined by a wire 453 to the wire 431. The coils 449 and 450 of the brake 87 are energized whenever the motor M is energized and serve to release the brake, the latter being applied by springs (not shown) whenever the supply of current to the motor M is interrupted.

The quadruple push button switch 425 comprises four push buttons identified by the legends "Jog reverse," "Jog forward," "Start," and "Stop." The jog-reverse switch includes contacts *g*, *h*, *s* and *t*, the jog-forward switch including contacts *j*, *k*, *l* and *m*, and the start and stop switches including contacts *n*, *o*, *p* and *r*. Extending from the wire 440 to the contacts *h*, *m* and *o* of the jog-forward, jog-reverse and start switches is a wire 455, the latter being connected to the contact *d* of the switch 423 by a wire 456. Connecting one end of the coil 446 of the switch 424 with the contact *g* of the jog-reverse switch is a wire 457. Extending from the contact *s* of the jog-reverse switch is a wire 458, the latter connecting the four switches 174 and the switch 266 in series as shown in Fig. 4 and terminating at the lowermost contact of the switch 72. Connecting the wire 458 with the uppermost contact of the switch 246 is a wire 460. Connecting to adjacent contacts of the switches 72 and 246 is a wire 461 which extends to the coil 434 of the switch 423. Connecting the wire 461 with the contact *l* of the jog-forward switch is a wire 462. The contacts *k* and *r* of the jog-forward and stop switches respectively are joined by a wire 463 and the contacts *n* and *p* of the start and stop switch are joined to a common wire 464 leading to the contact *c* of the magnetic switch 423. Joining the contact *t* of the jog-reverse switch with the contact *j* of the jog-forward switch is a wire 466.

The function of the electrical elements shown in Fig. 4 will be described at appropriate points during the following description of the operation of the machine 10.

Operation

Although the machine 10 of this invention is readily adjustable to make boxes of different sizes and shapes, it is shown in the accompanying drawings as being adjusted to make a box X of the shape shown in Fig. 1A, the sides S of the box X being nailed to the ends E by a pair of nails N and the bottom B secured to the ends E by four nails N'.

The first step in preparing the machine 10 for operation, is to load the magazines 150 and 151 (see Fig. 7), with end shook E and side shook S, this being done with the shook assembling form 15 positioned vertically in relation to the magazines 150 and 151 as shown in Fig. 13, the form 15 being on its down stroke when so positioned. After positioning the form 15 in this manner, the magazines 150 and 151 are filled with shook and the castings 159 (see Fig. 28B) are manually pulled outwardly against the tension of the springs 166 and 167 to enable positioning the rod 160 in back of the shook, the latter being urged against the form 15 by the springs 166 and 167 as shown in Fig. 28.

After supplying the magazines 150 and 151 with side shook S and end shook E, the magazine 224 (see Fig. 28) is supplied with bottom shook B, three pieces, B¹, B² and B³ of the latter being

placed on the angle irons 203 in front of the shook feeding dogs 295, 296 and 297 respectively.

Prior to starting the machine 10, a nail is dropped into each of the eight funnels at the upper ends of the nail tubes 420 in order to supply the vertical and horizontal chucks 385 and 346 respectively with nails, a few nails being placed in the nail runs 418 leading to the funnels. Manual placement of nails in this manner is necessary only when the machine 10 is first used, it being understood that the nail feeding mechanisms 402 and 403 operate entirely automatically after the machine 10 is started. It is also necessary, before starting the machine 10, to place a finished box on the angle irons 207 below the pointed bar 277 so as to hold the latter up in position to receive finished boxes therebeneath as the latter are ejected by the dogs 307.

The machine 10 requires two operators, one of whom remains at the front side of the machine within reach of the push button switch 425, this operator also keeping the front shook magazine 151 supplied with side shook S. The other operator keeps the rear magazine 151, side magazines 150 and bottom shook magazine 224 supplied with shook and also replenishes the supply of nails in the pans 404 when necessary.

After the machine 10 is thus made ready to start, the "start" switch button is momentarily pressed to close the magnetic switch 423 and start the motor M, the latter driving the crank shaft 48 (see Fig. 2) in the direction indicated by the arrow A. Rotation of the shaft 48 is transmitted through the crank 52, connecting rod 114, lever 107 and link 109 to the shook assembling form 15, the latter moving downward at the start from the position in which it is shown in Fig. 13 to that shown in Fig. 15. When the form 15 moves downward to the position shown in Fig. 14, the upper edges of the side and end shook S and E move in against the faces 123 and 124 respectively of the form 15 and when the latter moves to its lowermost position as shown in Fig. 15, the shook S and E moves into full engagement with the faces 123 and 124, this position being also shown in Fig. 28.

When the form 15 starts upward as shown in Fig. 16, the innermost pieces of shook S and E are engaged by the shoulders 121 and 122 respectively and lifted with the form 15. The pieces of side shook S are held securely against the side faces 123 of the form 15 as shown in Fig. 16 by the sharp edges 133 of the lugs 132 and the leaf springs 126. It will be noted in Fig. 19 that the innermost box ends E engaged by and lifted with the form 15 are retained against the form 15, during upward movement of the latter, by the angle iron portions 188 of the plates 184, the ends E being urged away from the form 15 and against the angle irons 188 by the spring pressed plungers 128 mounted in the end faces 124 of the head portion 118 of the form 15, details of the plungers 128 being shown in Figs. 11 and 12.

During vertical reciprocation of the shook assembling form 15, the pairs of rods 289 (see Fig. 17) reciprocate horizontally in timed relation with movement of the form 15, this being accomplished by the lever 64 (see Fig. 28A) which oscillates in response to rotation of the cam 57, movement of the lever 64 being transmitted to the rods 289 by means of the connecting rod 75 (see Figs. 28 and 28A), shaft 80 (see Fig. 28) and chains 292.

As the form 15 moves upward, the bottom shook feeding dogs 295, 296 and 297 move left-

ward to the position in which they are shown in Fig. 28 so as to slide the pieces B¹, B² and B³ of bottom shook leftward along the shook slides 205 and 206, the piece B¹ being supported by the ledges 282 of the box strippers 281. The pointed bars 272, shown in Figs. 18 and 28, serve to yieldably retain the pieces of bottom shook in their respective positions on the angle irons 208 to prevent displacement of these pieces during rightward movement of the dogs 295, 296 and 297 as viewed in Fig. 28. Leftward movement of the dogs 295, 296 and 297 continues during the initial period of upward movement of the form 15 until the pieces B¹ of bottom shook is moved to the position in which it is shown in Fig. 28.

In Fig. 28, the bottom shook feed dogs 295, 296 and 297 are disposed in their leftwardmost position, this resulting from the lever 64 (see Fig. 28A) being forced to its downwardmost position by the cam 57. It will also be noted in Fig. 28A that when the lever 64 is in this position the normally closed switch 72 is opened by the screw 79 mounted on the finger 69 of the lever 64. The switch 72 operates in conjunction with the switch 246 shown in Fig. 28, the purpose of these switches being to stop the machine 10 if the ejector dogs 305 should fail to eject a finished box as described hereinafter.

As the form 15 rises from the position in which it is shown in Fig. 28, the piece B¹ of bottom shook is carried upward by the form 15 and urged against the uppermost surface of the form 15 by the spring finger 251. During upward movement of the form 15, the piece B¹ of shook is shifted into vertical alignment with the form 15 by the flusher fingers 387 on the feet 386. As the form 15 moves upward between the yieldable flushing plates 328 shown in Fig. 19, these plates are urged apart slightly by the ends of the pieces of side shook S carried by the form 15 so that the distance between the plates 328 is equal to the length of the side and bottom shook, the normal distance between the plates 328, as indicated by the dimension line W in Fig. 19, being slightly less than the length of the side shook S and bottom shook B. The pieces of end shook E carried by the form 15 are urged against the plates 328 by the spring pressed plungers 128 of the form 15 so as to flush the ends of the side shook with the box ends. It is thus clear that the yieldable plates 328 compensate for slight variations in the length of the pieces of side and bottom shook and that the plungers 128 urge the pieces of end shook against the plates 328 regardless of variations in thickness of the end shook, thus producing a box in which the end pieces are flush with the ends of the sides and bottom thereof.

Fig. 29 shows the rising form 15 just as the piece B¹ of bottom shook engages the lower surfaces of the feet 386 and vertical chucks 385, the horizontal chucks 346 being spaced from the side shook S as shown. Upward movement of the form 15 from the position in which it is shown in Fig. 29 raises each of the heads 312 of the frame structures 12 and 13, the heads 312 sliding upward on the posts 41 and columns 45 to the position shown in Fig. 30, the vertical and horizontal nails N' and N being driven during vertical movement of the heads 312 in the following manner:

As the nail driving heads 388 are stationary on the columns 45, except for slight yieldability, the nail driving punches 392 extending downward from the heads 388 are forced into the chucks

385 as the latter rise with the heads 312 as shown in Fig. 30, thus forcing the vertical nails N' from the chucks 385, through opposite ends of the bottom B¹ and into the box ends E so as to nail the bottom to the ends. The horizontal nails N are driven in response to vertical movement of the heads 312 by the screws 332, the latter being rotated in the directions indicated by the arrows thereon in Fig. 19 by the racks 337 secured on the columns 45 meshing with rack pinions 333. The horizontal chuck carriers 340 and horizontal nail driving heads 315 (see Fig. 18) are screwed inward by the rotating screws 332 until the innermost faces of the horizontal chucks 346 engage the pieces of side shook S carried by the form 15. When the inward movement of the carriers 340 is arrested by contact of the chucks 346 with the side shook S, the nuts 348 (see Fig. 22) rotate within the carriers 340, thus urging the chucks 346 against the side shook S while the screws 332 continue to rotate. As aforementioned, the width of the box form 15 (the distance between the opposite side faces 123 shown in Fig. 8) is slightly greater than the inside width of the average finished box. The reason for this is that the end shook E is apt to vary slightly in length and if the width of the box form were not equal to or greater than the length of the longest pieces of end shook, the pieces of side shook S would be held away from the form 15 by the longest pieces of end shook and interfere with operation of the machine. As seen in Fig. 8, the endmost side faces 123 are spaced along the side of the form 15 from the end faces 124 thereof. This is to permit the side shook (see Figs. 8A and 8B) to flex inwardly into contact with slightly shorter pieces of end shook E during the nailing operation illustrated in Fig. 8B. As seen in Fig. 30, continued rotation of the screws 332 screws the nail driving heads 315 inward forcing the nail driving punches 380 into the horizontal chucks 346 so as to drive the nails N through the side shooks S and into the box ends E.

Fig. 30 shows the shook assembling form 15 at the top of its stroke with all the nails driven in the various pieces of shook assembled on the form 15 to form the box X. From this position, the form 15 starts downward and, as shown in Figs. 31 and 32, the finished box X is stripped from the form 15 by the strippers 281, the ledges 282 of the latter engaging the lower edges of the box ends E which overhang the shoulders 122 of the form 15 (see Fig. 33).

When the head 312 moves down following a nailing operation, its arrival at its lowermost position (see Fig. 31) is cushioned by the aforementioned rubber bumpers 44 provided on the bar 42.

As shown in Fig. 29, the leaf springs 126 remain between upper edges of the side shook S and the bottom B¹ after the box is nailed so as to retain the finished box on the form 15 during downward movement of the latter, these springs being sufficiently flexible to be pulled out from between the sides and bottom of the box as the latter is stripped from the form 15 by the strippers 281. After being stripped from the form 15, as seen in Figs. 31 and 32, the finished box X rests on the ledges 282 of the strippers 281 and is yieldably held in this position by the arms 251 and 255.

In Fig. 28, the shook feeding dogs 295, 296, 297 and the box ejecting dog 305 are moved to their leftwardmost positions, the lever 64 (see Fig.

28A) being at its lowermost position. As the form 15 moves upward from the position in which it is shown in Fig. 28 to the nailing position shown in Fig. 30 and downward to the box stripping position shown in Fig. 31, the dogs 295, 296, 297 and 305 move from their leftmost position shown in Fig. 28 to their rightmost position shown in Fig. 31. At this time the ejector dogs 305 are disposed in box ejecting position, the notches 130 of the form 15 providing clearance for the innermost ends of the dogs 305.

Movement of the box ejector dogs 305 is accelerated during the time they move into ejecting position (see Fig. 31) and remove the finished box from over the form 15 (see Fig. 28), this acceleration being necessary in order to prevent interference between the finished box and the rising form as very little time elapses from the time the box is stripped until the form 15 rises again to the position in which it is shown in Fig. 31. This acceleration of the dogs 305 is caused by the shape of the cam 57, rapid movement of the dogs 305 into the box ejecting position shown in Fig. 31 occurring when the roller 74 (see Fig. 31A) rolls into the depression 59 of the cam 57 causing the lever 64 to rise rapidly to its upwardmost position, rapid leftward movement of the dogs 305 from the position in which they are shown in Fig. 31 to that shown in Fig. 28 resulting from rapid movement of the lever 64 from its upwardmost position shown in Fig. 31A to its lowermost position shown in Fig. 28A in which the roller 74 passes over the lobe 58 of the cam 57.

As the bottom shook feeding dogs 295, 296 and 297 are mounted on the rods 289 which also carry the ejector dogs 305, movement of the feeding dogs is likewise accelerated so as to feed the piece of bottom shook B² (see Fig. 31) into position above the form 15 (see Fig. 28) before the form 15 rises to the position in which it is shown in Fig. 31.

The finished boxes are pushed along the angle irons 207 and 307, the latter serving to elevate the finished boxes away from the side shook magazine 151 therebeneath in order to provide sufficient room for supplying shook to the magazine 151. A suitable conveyor (not shown) is provided to receive the finished boxes from the angle irons 307 and convey these boxes from the machine 10. The pointed bars 277 (see Figs. 18 and 28), serve to prevent the finished boxes from being moved rightward as viewed in Fig. 28 by the dogs 305 when the latter are moving inward to box ejecting position.

Occasionally, during operation of the machine 10, the ejector dogs 305 fail to eject a finished box, this occurring when the piece of side shook engaged by the dogs 305 is defective or when the finished box, due to some irregularity, resists ejection to the extent that the side engaged by the dogs 305 splits or pulls loose from the box ends. When such a condition occurs, the switches 72 and 246 stop the operation of the machine 10 to enable the operator to remove the defective box. The manner in which the switches 72 and 246 function to stop the machine is as follows:

As seen in Fig. 28, the arm 256 is in its lowermost position, the finished box X having been drawn from under this arm by the dogs 305. When the arm 256 is in this position, the shaft 242 on which the arm 256 is fixed is rotated counter-clockwise sufficiently to cause the lever 244 on this shaft to close the normally open switch 246. At this point in the operation of

the machine 10, the normally closed switch 72 (see Fig. 28A) is opened by contact of the screw 10 on the arm 64. Whenever the switch 246 is closed at the time the switch 72 is momentarily opened, the machine 10 continues to operate, the switch 246 maintaining the circuit to the motor M at the time the switch 72 is opened. If the dogs 305 should fail to eject a finished box, the latter remains under the arm 256 holding the latter up in the position in which it is shown in Fig. 31, it being noted that when the arm 256 is held up in this position, the switch 246 is not contacted by the lever 244 and remains open. When the lever 244 fails to close the switch 246 at the time the switch 72 is opened as shown in Fig. 28A, the circuit to the motor M is broken, thus stopping the machine 10 to permit removal of the unejected box.

If the bottom shook magazine 244 should become empty or if the bottom shook feed dogs 291 fail to pick a piece of bottom shook B from the magazine 224, the missing piece causes the arm 267 (see Fig. 28) to swing downward rotating the shaft 264 counterclockwise and causing the lever 265 (see Fig. 25) to engage and open the normally closed switch 266. This stops the motor M to permit the operator to supply the missing piece of shook.

As shown in Fig. 7, each of the four magazines 150 and 151 is provided with one of the aforesigned switches 174, these being provided to stop the machine 10 if the supply of shook in any one of these magazines is reduced beyond a given point. When the collar 169 (see Fig. 24) forces the rod 175 against the switch 174, the latter is opened so as to break the circuit to the motor M, the switch 174 being again closed when the supply of shook is replenished and the casting 159 moved outward.

The manner in which end and side shook magazines 150 and 151 are filled without interrupting operation of the machine 10 is shown in Fig. 28B. When the supply of shook becomes low in any of the four magazines 150 or 151, as illustrated by the amount of shook S in the magazine 151 shown in Fig. 28B, the operator fills the empty portion of the magazine 151 with a stack of shook as indicated at S'. While applying pressure on the stack S' with one hand, the operator pulls the handle 162 downward with the other hand so as to withdraw the rod 160 from between the shook S and the stack S'. After withdrawing the rod 160, the operator continues pushing on the stack S', slides the casting 159 outward on the rods 158 and lifts the handle 162 to place the rod 160 in engagement with the end of the stack S'.

During the operation of the machine 10, the nail pans 404 (see Fig. 1) are oscillated continuously by the connecting rods 406 extending from the cranks 98 (see Fig. 3) on the shaft 97. The pans 404 keep the nail runs 418 (see Fig. 2) supplied with rows of nails in a familiar manner. The nail pick bars 407 (see Figs. 1 and 2) are reciprocated in response to vertical movement of the heads 312 by the cams 413, the latter being connected with the heads 312 by the aforementioned rods 414. At each reciprocation of the pick bars 407, a nail is dropped into each of the funnels at the upper ends of the 70 nail tubes 420 in a manner familiar in the art.

The procedure for adjusting the machine 10 to make a box of a different size from the box X shown in Fig. 1A, is as follows:

The form 15 is replaced by a similar form 75

(not shown) shaped to fit the box to be made, it being found advisable in practice to provide individual forms for each different box size rather than furnish a single adjustable form to accommodate a number of box sizes. If necessary, additional horizontal chucks 346 and punches 380 therefor are mounted on the carriers 340 and positioned to drive the horizontal nails at the desired points in the box to be made. Additional nail tubes 420 are provided to connect the additional chucks with funnels 418, the closed nail runs between the bars 417 (see Fig. 2) being opened wherever necessary by moving the bars 417 apart. In the same manner, additional vertical chucks 385 may be mounted on the gibs 383 if it is desired to drive more than four nails into the box bottom.

The nuts 40^a on the bolts 40 (see Fig. 7) are loosened to permit adjusting the frame structures 12 and 13 laterally until the dimension "W" of Fig. 19 is slightly less than the length of the box to be made, it being seen in Fig. 7 that the angle irons 153 of the magazines 151 move with the frame structures 12 and 13 so that adjustment of the frame also results in adjustment of the magazines 151. The width of the end shook magazines 150 is adjusted by loosening the bolts 155 and 177 to permit moving the angle irons 153 of the magazines 150 until the space therebetween is slightly greater than the length of the end shook to be used.

When making boxes of greater depth than the box X shown in Fig. 1A, the posts 41 may be raised by loosening the set screw 36 (see Fig. 7), in order to increase the space between the heads 312 and the magazines 150 and 151. It is also necessary, in order to make boxes of greater depth, to increase the length of stroke of the shook assembling form 15, this being accomplished by moving the upper end of the connecting rod 114 from the hole 110 (see Fig. 2) to either of the holes 111 or 112 depending on the stroke required.

If the width of the box to be made is substantially more or less than the width of the box X shown, the stroke of the bottom shook feed dogs 295, 296 and 297 and ejecting dog 305 may be increased or decreased by mounting the lower end of the connecting rod 75 (see Fig. 6) on the hole 66 or 68 of the lever 64.

The jog reverse switch and the jog forward switch, shown in the wiring diagram of Fig. 4, operate respectively when depressed to run the machine in a reverse or forward direction only so long as one of these switches is held down. The purpose of these switches is to give the opportunity to jog the machine for a very slight movement in order to make adjustments and to get the machine in running order again after one of the safety switches has caused the machine to stop.

We claim:

1. In a box making machine, the combination of: a frame; magazines on said frame containing side, end and bottom shook; a form adapted to receive a set of shook from said magazines in assembled relation to form a box; power means causing relative movement between said magazines and said form; and means for nailing said shook together while supported in said assembled relation on said form, said nailing means being actuated in response to said relative movement between said magazines and said form.

2. In a box making machine, the combination of: a frame; magazines on said frame contain-

ing side, end and bottom shook; a form adapted to receive a set of shook from said magazines and to support said shook in assembled relation to form a box; power means causing relative movement between said magazines and said form; and means for nailing said shook together to form a box during said relative movement and while said shook is supported in assembled relation by said form.

3. In a box making machine, the combination of: a frame; magazines on said frame containing side, end and bottom shook; a form adapted to receive a set of shook from said magazines and to support said shook in assembled relation to form a box; power means causing relative movement between said magazines and said form; and means for nailing said shook together to form a box during said relative movement and while said shook is supported in assembled relation by said form, said nailing means being actuated in response to said relative movement between said magazines and said form.

4. In a box making machine, the combination of: a frame; a reciprocating form mounted on said frame; power means for actuating said form; means for supplying a set of box shook, including sides, ends and a bottom, to said form, said shook being supported by said form in assembled relation to form a box; and means for nailing said shook together during movement of said reciprocating form and while said shook is supported in assembled relation on said form.

5. In a box making machine, the combination of: a frame; a reciprocating form mounted on said frame; power means for actuating said form; means for supplying a set of box shook, including sides, ends and a bottom, to said form, said shook being supported by said form in assembled relation to form a box; and means for nailing said shook together during movement of said reciprocating form and while said shook is supported in assembled relation on said form, said nailing means being actuated in response to movement of said reciprocating form.

6. In a box making machine, the combination of: a frame; magazines on said frame containing side, end and bottom shook; a form adapted to select a set of shook from said magazines and support said shook in assembled relation to form a box; power means causing relative movement between said magazines and said form; means for nailing the bottom of said set of shook to the side and end pieces thereof; and screw operated means responsive to said relative movement for nailing said side and end pieces together.

7. A combination as in claim 6, in which said means for nailing the bottom of said set of shook to the side and end pieces thereof is operated in response to said relative movement between said magazines and said form.

8. In a box making machine, the combination of: a frame; a reciprocating form mounted on said frame; power means for actuating said form; means for supplying a set of box shook, including sides, ends and bottom, to said form, said shook being supported by said form in assembled relation to form a box; nailing means disposed in the path of movement of said form to nail said box bottom in position; and screw operated means functioning during said movement to drive nails transversely of the direction of said movement to nail said box sides and ends together.

9. A combination as in claim 8, in which said

75 screw means is actuated in response to movement of said reciprocating form.

10. In a machine for making boxes of different sizes, the combination of: a frame; a pair 5 of unitary structures mounted on said frame, said structures being adjustable toward and away from each other in accordance with the size of box to be made; means for supporting a set of box shook in assembled relation without being nailed together to form a box; means for causing relative movement between said structures and said shook supporting means; and means on each of said structures for nailing the bottom and sides of said box to one end thereof without turning the box.

11. In a machine for making boxes of different sizes, the combination of: a frame; a pair 20 of unitary structures mounted on said frame, said structures being adjustable toward and away from each other in accordance with the size of box to be made; means for supporting a set of box shook in assembled relation without being nailed together to form a box; means for causing relative movement between said structures and said shook supporting means; and means 25 on each of said structures which functions during relative movement between said shook supporting means and said structures to nail the bottom and sides of said box to one end thereof without turning the box.

12. In a machine for making boxes of different sizes, the combination of: a frame; a pair 30 of unitary structures mounted on said frame, said structures being adjustable toward and away from each other in accordance with the size of box to be made; means for supporting a set of box shook in assembled relation without being nailed together to form a box; means for causing relative movement between said structures and said shook supporting means; and means 35 on each of said structures which is responsive to relative movement between said shook supporting means and said structures to nail the bottom and sides of said box to one end thereof without turning the box.

13. In a machine for making boxes of different sizes, the combination of: a frame; a pair 40 of unitary structures mounted on said frame, said structures being adjustable toward and away from each other in accordance with the size of box to be made; a slidable head on each of said structures; means for supporting pieces of shook assembled in the same relation these will have when united to form a box; power means for 45 reciprocating said shook supporting means between said unitary structures; means on said heads for driving nails transversely of the direction of said reciprocation for securing said shook together as assembled, said heads being moved relative to said structures by said shook supporting means; and means responsive to 50 movement of said heads for actuating said nailing means.

14. In a machine for making boxes of different sizes, the combination of: a frame; a pair 55 of unitary structures mounted on said frame, said structures being adjustable toward and away from each other in accordance with the size of box to be made; a slidable head on each of said structures; means for supporting pieces of shook assembled in the same relation these will have when united to form a box; power means for reciprocating said shook supporting means between said unitary structures; nailing means for 60 driving nails parallel to the direction of move-

ment of said heads relative to said structures to nail the bottom of a box to the ends thereof; nailing means on each of said heads for driving nails transversely of the direction of movement of said heads to nail the sides of said box to one end thereof; and means for actuating said last mentioned nailing means.

15. A combination as in claim 14, in which the nailing means on each of said heads is actuated in response to movement of said heads relative to said frame structures.

16. In a nailing mechanism for driving nails into opposite sides of a piece of work, the combination of: means for supporting said work; opposed nail receiving chucks spaced to receive said work therebetween; nail driving elements for driving nails from said chucks into said work; and a single screw disposed parallel with said driving elements for actuating the driving elements of both of said opposer chucks simultaneously.

17. In a nail driving mechanism, the combination of: a frame; a chuck movably mounted on said frame for receiving and supporting a nail to be driven into a piece of work; a screw rotatable in said frame, the axis of rotation of said screw being parallel with the plane of movement of said chuck; a nut rotatably mounted on said chuck and threaded on said screw; friction means on said chuck for yieldably resisting rotation of said nut; a nail driving member for driving said nail from said chuck into said work; means for threadedly associating said nail driving member and said screw; and power means for rotating said screw to yieldably move said chuck into engagement with said work and positively move said nail driving member.

18. In a box making machine, the combination of: a frame; a pair of unitary structures mounted on said frame and adjustable toward and away from each other in accordance with the size of the box to be made on said machine; a plurality of shook receiving magazines mounted on said unitary structures; a reciprocating form adapted to receive a set of shook from said magazines in assembled relation to form a box; and nailing means on each of said unitary structures for nailing the bottom and sides of said box to one end thereof.

19. A combination as in claim 18, in which said nailing means is actuated in response to reciprocation of said form.

20. In a box making machine, the combination of: a frame; shook magazines on said frame containing box ends, sides and bottoms; a reciprocating form adapted to receive and support a set of said shook; means for nailing said shook together to form a box; an ejector for removing finished boxes from said machine; and means responsive to failure of said ejector to eject a finished box to stop said reciprocating form.

21. In a shook feeding mechanism for use in a box making machine, the combination of: a frame; a magazine containing a supply of shook; feed means for feeding a series of shook in progressive stages from said magazine toward a shook assembling station, the foremost piece of shook of said series being delivered to said station for assembly with other pieces of shook to form a box; and control means adapted to stop the operation of said machine in response to a gap in said series of shook resulting from malfunction of said means.

22. In a box making machine, the combination of: a frame; a shook assembling form recip-

rocable in a given path, said form being adapted to receive a set of shook including box ends and sides and to support said shook assembled in the right relation to form a box; a magazine on said frame containing box bottom shook; feed means for moving a series of pieces of bottom shook in progressive stages from said magazine toward the path of movement of said form, the foremost piece of shook in said series being moved into the path of said shook assembling form, each piece of shook in said series being advanced one stage for each reciprocation of said form; and means for nailing said assembled shook and said foremost piece of bottom shook together to form a box.

23. In a box making machine, the combination of: a frame; a shook assembling form reciprocable in a given path, said form being adapted to receive a set of shook including box ends and sides and to support said shook assembled in the right relation to form a box; a magazine on said frame containing box bottom shook; feed means for moving a series of pieces of bottom shook in progressive stages from said magazine toward the path of movement of said form, the foremost piece of shook in said series being moved into the path of said shook assembling form, each piece of shook in said series being advanced one stage for each reciprocation of said form; means for nailing said assembled shook and said foremost piece of bottom shook together to form a box; and a box ejector mounted on said bottom shook feed means for removing finished boxes from the path of movement of said form.

24. In a box making machine, the combination of: a frame; a shook assembling form reciprocable in a given path, said form being adapted to receive a set of shook including box ends and sides and to support said shook assembled in the right relation to form a box; a magazine on said frame containing box bottom shook; reciprocating feed means for feeding a piece of box bottom shook from said magazine into the path of said form; power means for actuating said feed means, said power means being adapted to move said feed means toward said path at a substantially greater rate of speed than the rate at which said feed means is moved away from said path; and means for nailing said assembled shook and said piece of bottom shook together to form a box.

25. In a box making machine, the combination of: a frame; a shook assembling form reciprocable in a given path, said form being adapted to receive a set of shook including box ends and sides and to support said shook assembled in relation to form a box; a magazine on said frame containing box bottom shook; reciprocating feed means for feeding a piece of box bottom shook from said magazine into the path of said form; power means for actuating said feed means, said power means being adapted to move said feed means toward said path at a substantially greater rate of speed than the rate at which said feed means is moved away from said path; means for nailing said assembled shook and said piece of bottom shook together to form a box; and a box ejector mounted on said reciprocating feed means for removing finished boxes from the path of said form, said box ejector removing a box from said path just in advance of the delivery by said feed means of a piece of bottom shook into said path.

26. In a box making machine, the combination of: a frame; magazines on said frame containing

box end and side shook; shook assembling means reciprocable in a given path for picking a set of shook from said magazines and supporting said shook assembled in relation to form a box; a magazine containing box bottom shook; feed means for moving a series of pieces of bottom shook in progressive stages from said magazine, the foremost piece of shook in said series being moved into the path of said shook assembling means for engagement thereby, each piece of shook in said series being advanced one stage during one reciprocation of said shook assembling means; means for nailing said assembled shook together to form a box; and a box ejector mounted on said bottom shook feed means for removing finished boxes from the path of movement of said form.

27. In a box making machine, the combination of: a frame; magazines containing box end and side shook, said magazines being positioned in a given plane on said frame; nailing mechanism on said frame, for nailing said end shook to said side shook, the position of said nailing mechanism being spaced in relation to the plane of said magazines; a slideway positioned in a plane between the plane of said magazines and the position of said nailing mechanism; a reciprocating shook assembling form movable in a path extending through the plane of said magazines and through said slideway into operative relation with said nailing mechanism; means for feeding box bottoms along said slideway into the path of said form, a set of shook comprising box ends, sides and a bottom being assembled on said form as the latter moves through the plane of said magazines and through said slideway; and nailing mechanism for nailing said bottom to said shook.

28. A combination as in claim 27, in which said nailing mechanism is actuated in response to movement of said shook assembling form.

29. In a box making machine, the combination of: a frame; magazines containing box end and side shook, said magazines being positioned in a given plane on said frame; nailing mechanism on said frame for nailing said end shook to said side shook and for nailing a bottom to said shook, the position of said nailing mechanism being spaced in relation to the plane of said magazines; a slideway positioned in a plane between the plane of said magazines and the position of said nailing mechanism; a reciprocating shook assembling form movable in a path extending through the planes of said magazines and said slideway; means for feeding box bottoms along said slideway into the path of said form, box end shook, side shook and a bottom being assembled on said form as the latter moves through the plane of said magazines and through said slideway, said shook and said bottom being nailed together to form a box by said nailing mechanism; and box stripping and ejecting means provided in the plane of said slideway for stripping a finished box from said form and moving said finished box along said slideway out of the path of movement of said form.

30. A combination as in claim 29, in which said box ejecting means is carried by said means for feeding box bottoms along said slideway.

31. In a box making machine, the combination of: a frame; a reciprocating shook assembling form on said frame; a slideway extending transversely through the path of movement of said form; means for yieldably mounting portions of said slideway disposed in the path of said

form; means for supplying box end and side shook to said form; feed means for feeding a piece of bottom shook along said slideway onto said yieldable portions, said bottom shook being engaged by said form as the latter passes through the plane of said slideway; nailing means for nailing said shook together to form a box while said shook is supported on said form, said finished box being stripped from said form by the yieldable portions of said slideway upon the return movement of said form.

32. In a box making machine, the combination of: a frame; a reciprocating shook assembling form on said frame; a slideway extending transversely through the path of movement of said form; means for yieldably mounting portions of said slideway disposed in the path of said form; means for supplying box end and side shook to said form; feed means for feeding a piece of bottom shook along said slideway onto said yieldable portions, said bottom shook being engaged by said form as the latter passes through the plane of said slideway; nailing means for nailing said shook together to form a box while said shook is supported on said form, said finished box being stripped from said form by the yieldable portions of said slideway upon the return movement of said form; and means for moving said stripped box along said slideway out of the path of said form.

33. A combination as in claim 32, in which said means for moving said stripped box along said slideway is connected with said bottom shook feed means.

34. In a box making machine, the combination of: a frame; a reciprocating shook assembling form on said frame; a slideway extending transversely through the path of movement of said form; means for yieldably mounting portions of said slideway disposed in the path of said form; means for supplying box and side shook to said form; a bottom shook magazine; means for feeding a series of pieces of bottom shook in progressive stages from said magazine along said slideway toward the path of said form, the foremost piece of shook of said series being fed onto the yieldable portions of said slideway for engagement by said form as the latter passes through the plane of said slideway; nailing means for nailing said shook together to form a box while said shook is supported on said form, said finished box being stripped from said form by the yieldable portions of said slideway upon the return movement of said form.

35. In a box making machine, the combination of: a frame; a reciprocating shook assembling form on said frame; a slideway extending transversely through the path of movement of said form; means for yieldably mounting portions of said slideway disposed in the path of said form; means for supplying box end and side shook to said form; a bottom shook magazine on said slideway; means for feeding a series of pieces of bottom shook in progressive stages from said magazine along said slideway toward the path of said form, the foremost piece of shook of said series being fed onto the yieldable portions of said slideway for engagement by said form as the latter passes through the plane of said slideway; nailing means for nailing said shook together to form a box while said shook is supported on said form, said finished box being stripped from said form by the yieldable portions of said slideway upon the return movement of said form; and box ejector means for moving said stripped

box along said slideway out of the path of said form, said ejector means being connected with said bottom shook feeding means to eject a finished box during each stage of movement of said series of pieces of bottom shook.

36. In a box making machine, the combination of: a plurality of box part magazines discharging box parts inwardly to positions just within the various sides of a polygon, each of said magazines including a pair of spaced guide members for guiding box parts contained therein, adjacent guide members being integrally connected together at their inner ends to form units; means for picking box parts from the discharge ends of said magazines so that the outer limits of said parts lie just within the sides of said polygon and feeding said box parts upwardly in the same relation as thus picked; a plurality of corner plates, each of which is mounted on one of said units and disposed about one of the angles of said polygon and overlies the box parts disposed in said magazines adjacent said angle excepting the box parts positioned to be fed immediately from said magazines and lying within the sides of said polygon as aforesaid; and means permitting the alteration of the relative positions of said units to vary the spacing of said guide members in the respective magazines to change said machine to make a box of a different size.

37. A combination as in claim 36, in which said corner plates are adjustably mounted on said units to accommodate box parts of different thickness than those previously handled.

38. In a shook assembling mechanism for use in a box making machine, the combination of: a shook assembling form for receiving a set of box shook comprising ends, sides and a bottom, said form supporting said set of shook in assembled relation to form a box; a pair of spaced, yieldable flusher plates; means causing relative movement between said plates and said form to cause said plates to engage opposite ends of the side and bottom shook disposed on said form; and means on said form for urging said end shook against said plates to flush the outer surfaces of said end shook with the ends of said side and bottom shook.

39. In a box making machine, the combination of: a frame; a shook assembling form for receiving a set of box shook comprising ends, sides and a bottom; means on said form for yieldably retaining said side shook thereon; a pair of spaced, yieldable flusher plates on said frame; power means causing relative movement between said plates and said form, said plates engaging opposite ends of the side and bottom shook on said form in response to said relative movement; means for urging the end shook on said form against said plates to flush outer surfaces of said end shook with ends of said side and bottom shook; and nailing means on said frame for nailing said shook together while so assembled on said form.

40. In a box making machine, the combination of: a frame; a reciprocating shook assembling form on said frame for receiving a set of shook comprising ends, sides and a bottom and supporting said shook assembled in relation to form a box; shoulders provided on said form for supporting said shook; yieldable fingers engaging said pieces of side shook and co-operating with said shoulders to retain said shook yieldably on said form; a pair of spaced, yieldable flusher plates on said frame, said plates engaging opposite ends of the side and bottom shook on said

form during reciprocation of said form; means on said form for urging said end shook against said plates to flush outer surfaces of said end shook with ends of said side and bottom shook; and nailing means on said frame for nailing said shook together to form a box while said shook is assembled on said form.

41. In a machine for making boxes of different sizes, the combination of: a frame; a pair of structures mounted on said frame, said structures being adjustable toward and away from each other in accordance with the size of box to be made; a shook receiving and assembling form between said structures; a plurality of shook magazines for supplying shook to said assembling form, each of said magazines including spaced shook supporting members mounted on said structures, the width of said magazines being adjustable in response to adjustment of said structures; and nailing means on said structures for nailing the shook assembled on said form together to form a box, said nailing operation being accomplished in response to the reciprocation of said form.

42. A shook assembling form, comprising: a body for supporting end, side and bottom shook assembled in relation to be nailed together to form a box in which the sides and bottom overlap the ends thereof; means on said form for engaging inside faces of said side shook at points spaced from the ends of said shook, the distance between the inside faces of said side shook, while so supported on said form, being greater than the inside width of the box to be made, end portions of said side shook flexing inwardly into contact with said box ends in response to said nailing operation; and means to retain said side shook on said form.

43. A shook assembling form, comprising: a body for supporting end, side and bottom shook assembled in relation to be nailed together to form a box; shoulders provided on said form for supporting one edge of each piece of said end and side shook; and yieldable fingers engaging the edges of said side shook opposite the edges thereof supported by said shoulders, said fingers urging said shook against said shoulders to retain said side shook yieldably on said form.

44. A shook assembling form, comprising: a body for supporting end, side and bottom shook assembled in relation to be nailed together to form a box; shoulders provided on said form for supporting one edge of each piece of said end and side shook; sharpened projections provided on the shoulders to engage said side shook and prevent accidental displacement of said shook from said form; and yieldable fingers engaging the edges of said side shook opposite the edges thereof supported by said shoulders, said fingers urging said shook against said shoulders to retain said side shook yieldably on said form.

45. A shook assembling form, comprising: a body adapted to support pieces of side, end and bottom shook assembled in relation to be nailed together to form a box in which the sides and bottom overlap the ends thereof; shoulders formed on said body to support edges of said end and side shook; yieldable fingers on said body for retaining said side shook on said form; means on said form for engaging inside faces of said side shook at points spaced from the ends of said shook, the distance between the inside faces of said side shook, while so supported on said form, being greater than the inside width of the box to be made, end portions of said side

shook flexing inwardly into contact with said box ends in response to said nailing operation.

46. A shook assembling form, comprising: a body adapted to support pieces of side, end and bottom shook assembled in relation to be nailed together to form a box in which the sides and bottom overlap the ends thereof; shoulders formed on said body to support edges of said end and side shook; yieldable fingers on said body for urging said side shook against the shoulders supporting said shook; sharpened projections on the shoulders supporting said side shook, said fingers and said projections co-acting to prevent accidental displacement of said side shook from said form; means on said form for engaging inside faces of said side shook at points spaced from the ends of said shook, the distance between the inside faces of said side shook, while so supported on said form, being greater than the inside width of the box to be made, end portions of said side shook flexing inwardly into contact with said box ends in response to said nailing operation.

47. In a box making machine, the combination of: a shook assembling form adapted to receive side, end and bottom shook and support said shook in proper relation to form a box; means for nailing said shook together while so assembled; means for reciprocating said form to and from said nailing mechanism to accomplish said nailing operation; and means for yieldably retaining the finished box on said form so as to resist the frictional removal of said box from said form during the return movement of said form away from said nailing mechanism.

48. In a box making machine, the combination of: a form adapted to receive a set of shook and support said shook in assembled relation to form a box; shoulders provided on said form for positioning the shook forming the sides and end walls of said box; yieldable fingers on said form extending between the bottom of said box and the edges of certain of the shook forming said box walls; means for nailing said shook together while so assembled; and means for reciprocating said form to and from said nailing mechanism, said fingers retaining said box on said form so as to resist the frictional removal of said box from said form during the return movement of said form away from said nailing mechanism.

49. In a box making machine, the combination of: a form adapted to receive a set of shook and support said shook in assembled relation to form a box; shoulders provided on said form for positioning the shook forming the sides and end walls of said box; yieldable fingers on said form extending between the bottom of said box and the edges of certain of the shook forming said box walls; means for nailing said shook together while so assembled; means for reciprocating said form to and from said nailing mechanism, said fingers retaining said box on said form so as to resist the frictional removal of said box from said form during the return movement of said form away from said nailing mechanism; and means for stripping said box from said form during said return movement.

50. In a box making machine, the combination of: a frame; a form on said frame for receiving a set of box shook comprising ends, sides and a bottom and supporting said shook in assembled relation to form a box; means on said form to support inner faces of said side shook at points spaced from the ends of said shook to permit end portions of said side shook to flex inwardly to-

ward said form; yieldable flusher plates on said frame for engagement with opposite ends of said side and end shook; means on said form for urging said end shook against said plates to flush outer surfaces of said end shook with the ends of said side and bottom shook; and nailing means for nailing said side and bottom shook to said end shook to form a box, end portions of said side shook flexing inwardly against said end shook in response to said nailing operation.

51. In a box making machine, the combination of: a frame; a shook assembling form for receiving a set of box shook comprising ends, sides and a bottom; means on said form for yieldably retaining pieces of said side shook thereon; means on said frame for retaining pieces of said end shook on said form; and nailing means on said frame for nailing said shook together to form a box while said shook is assembled on said form.

52. In a box making machine, the combination of: a form for receiving box end, side and bottom shook and supporting said shook in position to form a box; nailing means for nailing said shook together; means for stripping said box from said form after said nailing operation; and an ejector for removing said box from said machine, said ejector engaging an inside surface of said box, said form being shaped to permit said ejector to move into ejecting position prior to removal of said box from said form.

53. In a box making machine, the combination of: a form for receiving box end, side and bottom shook and supporting said shook in position to form a box; nailing means for nailing said shook together; power means for moving said form to and from said nailing means; means for stripping the nailed box from said form during return movement of said form from said nailing means; and an ejector for engaging an inside surface of said finished box and removing said box from said machine, a portion of said form being cut away to permit said ejector to move into box ejecting position prior to removal of said box from said form.

54. In a machine for making boxes, the combination of: a frame; a pair of spaced structures; a pair of heads, one of which is provided on each of said structures, said heads being slidable on said structures in a given direction; means for carrying pieces of shook assembled in the same relation these will have when united to form a box; power means causing relative movement in said direction between said shook carrying means and said unitary structures, said slidable heads being contacted in said movement by said carrying means to cause relative movement between said slidable heads and said structures; and means on said slidable heads for driving nails into said shook transversely of the direction of said relative movement for securing said shook together as assembled.

55. In a machine for making boxes of different sizes, the combination of: a frame; a pair of spaced structures mounted on said frame, said structures being adjustable toward and away from each other in accordance with the size of box to be made; a pair of heads, one of which is provided on each of said structures, said heads being slidable on said structures in a given direction; means for carrying pieces of shook assembled in the same relation these will have when united to form a box; power means causing relative vertical movement between said shook carrying means and said unitary structures, said slidable heads being contacted in said movement

by said carrying means to cause relative movement between said slideable heads and said structures; and means on said slideable heads for driving nails into said shook transversely of the direction of said relative movement for securing said shook together as assembled.

56. In a machine for making boxes, the combination of: a frame; a pair of spaced structures; a pair of heads, one of which is provided on each of said structures, said heads being slideable on said structures in a given direction; means for carrying pieces of shook assembled in the same relation these will have when united to form a box; power means causing relative movement in said direction between said shook carrying means and said unitary structures, said slideable heads being contacted in said movement by said carrying means to cause relative movement between said slideable heads and said structures; means on said slideable heads for driving nails into said shook transversely of the direction of said relative movement for securing said shook together as assembled; and means responsive to said relative movement between said heads and said structures for actuating said nail driving means.

57. In a box nailing machine, the combination of: a frame; a form adapted to receive side and end shook in assembled relation; means causing movement of said form along a given straight path; magazine means for feeding side and end shook onto said form in a given plane disposed transversely of said path; magazine means for feeding bottoms into assembled relation with said sides and ends on said form, said bottoms being thus fed to said form in a plane disposed transversely relative to said path so that said form receives said bottom after receiving said sides and ends and thereafter continues said movement; and means operating during movement of said form and disposed adjacent said path beyond the point therein where said form passes through the plane in which it receives said bottom, for nailing said assembled sides, ends, and bottom together.

58. In a nailing machine, the combination of: a main base, the upper end of which lies substantially in a horizontal plane; a pair of frame structures mounted on said base and extending

upwardly therefrom, each of said frame structures including a cross member fixed for horizontal adjustment on said base, a pair of spaced vertical posts mounted on said cross member, and a head member connecting upper ends of said posts; side and end shook magazines mounted on said cross members for containing a supply of sides and ends and feeding the same to a central vertical assembly path between said structures; a shook assembly form adapted to reciprocate along said path to receive said sides and ends in assembled relation; and nailing mechanisms, one of which is mounted on each of said structures for uniting said sides and ends in the relation in which they are assembled on said form when said form arrives in proximity to said nailing mechanisms.

59. In a nailing machine, the combination of: a main base, the upper end of which lies substantially in a horizontal plane; a pair of frame structures mounted on said base and extending upwardly therefrom, each of said frame structures including a cross member fixed for horizontal adjustment on said base, a pair of spaced vertical posts mounted on said cross member, and a head member connecting upper ends of said posts; side and end shook magazines mounted on said cross members for containing a supply of sides and ends and feeding the same to a central vertical assembly path between said structures; a bottom magazine and feed means including a pair of spaced bottom guides, each of which is mounted on one of said structures for feeding bottoms one at a time into said path; a shook assembly form adapted to reciprocate along said path to receive said sides, ends, and a bottom in assembled relation; and nailing mechanisms, one of which is mounted on each of said structures for uniting said sides, ends, and bottom in the relation in which they are assembled on said form when said form arrives in proximity to said nailing mechanism.
